UNITED STATES PATENT OFFICE.

JOHN C. LITTLE, OF CHICAGO, ILLINOIS, ASSIGNOR TO H. G. DORAN & CO., A CORPORATION OF ILLINOIS.

FOOTBOARD.

Application filed August 9, 1922. Serial No. 580,597.

To all whom it may concern:

Be it known that I, JOHN C. LITTLE, a citizen of the United States, residing at Chicago, in the county of Cook and State of Illinois, have invented certain new and useful Improvements in Footboards, of which the following is a specification.

This invention relates to foot-boards.

It will be explained as applied to a running board for railway cars and the like.

As employed on railway cars the foot-board comprises, in general, a wire open-meshed fabric tread and a framework for supporting the fabric above the roof. The woven wire tread, separated from the roof, provides a roughened openwork surface along which brakemen and others may walk with greater safety than when a wooden running board is employed.

One of the objects of this invention is to provide an improved foot-board.

Another object is to provide a foot-board having a woven wire tread.

Another object is to provide an improved support for a foot-board.

Another object is to provide a foot-board having improved means for properly aligning and anchoring adjacent ends of adjoining sections.

Another object is to provide a foot-board which is reliable and relatively inexpensive to apply and maintain.

Other objects and advantages will herein-after appear.

An embodiment of the invention is illustrated in the accompanying drawing, wherein

Fig. 1 is a top plan of two sections of foot-board.

Fig. 2 is a side elevation thereof.

Fig. 3 is a section on the line 3—3 of Fig. 1.

Fig. 4 is a section approximately on the line 4—4 of Fig. 3, one of the support saddles being broken away to show the method of anchoring the end of the fabric, and

Fig. 5 is an enlarged perspective of one of the bolt-protecting clips.

The foot-board may be prepared in sections of suitable length to facilitate manufacture, handling and application. The width of the sections may be regulated to meet the various conditions of the required service.

Each foot-board section comprises a substantially rectangular framework composed of two longitudinal side rails 1 and transverse rails 2 secured together by rivets, welds or other appropriate means. The side rails may be made from angle iron and the transverse rails of rather rigid strap iron. The number and position of the transverse rails will depend somewhat upon the length of the foot-board sections.

The opposite ends of the transverse rails are bent to form supporting terminal legs 3 and feet 4. The mid-section of each transverse rail 2 may be bent into substantially U shape to form center transverse supporting legs 5 and an interconnecting foot 6. The transverse rails with their terminal and central supporting legs and feet form saddles for anchoring the foot-board in place and supporting the tread suspended above the roof.

The tread comprises a wire open-mesh fabric 7. The fabric may be made by weaving wire strands together after the manner of preparing wire fencing. The mesh should be so small that even the heel of a man's shoe will not become wedged therein. Various shapes of wire may be used but it is believed that shapes other than of circular cross-section are to be preferred. For example, if wires of rectangular cross section are used they may be woven or joined together in such a way as to present an angle rather than a flat or curve at the tread surface. This condition is especially desirable at the joints where the wire strands twist about each other or come together, as slight, relatively sharp projections will occur at the joints. The fabric will thus be caused to present a relatively rough non-slipping tread to the feet of the person walking thereon. If desired the wire strands may be welded, brazed or otherwise securely fastened together at the joints in the fabric.

The longitudinal edges of the wire fabric are bent over one of the webs or rails 1, as most clearly shown in Fig. 3. In a similar manner the ends of the fabric may be bent over the transverse rails 2 as most clearly shown in Fig. 4. The permanent set of the wire ordinarily will be sufficient to hold the fabric properly stretched over the framework and support the usual loads to be borne.

If additional anchorage is necessary the fabric may be riveted, bolted or otherwise secured to the framework.

Adjacent ends of adjoining foot-board sections 5 may be jointly anchored to the car roof or other support by means of stirrups 8. These stirrups have a substantially U-shaped central portion and oppositely projecting flanges. The central foot 6 of a saddle may 10 be securely fastened to the proper flange of a stirrup by a bolt 9. Each stirrup 8 may be anchored to the roof by a bolt 10 passing through the car roof ridge. A small metal clip 11 may be interposed between feet 6 15 and the stirrup and bridge the channel between the stirrup flanges to cover the head of bolt 10. The clip may have depending aprons or ears 12 on opposite sides to close the sides of the channel about the head of bolt 10. The holding or anchoring bolts are thus 20 protected against the collection and retention of moisture in the stirrup channels.

Ordinarily, for railway car service, it is sufficient and the better practice to secure 25 the fabric supporting framework only by the bolts through the ridge of the roof, leaving the outside feet of the saddles unsecured. The skewing or twisting movement of the car will not then seriously affect the anchorages 30 and the perforation of the roof is reduced to a minimum.

The improved foot-board affords a tread on which ice, snow or water can not collect and remain. The open mesh and separation 35 from the supporting roof provide ready drainage. If some ice should collect on the tread the movements of the car in motion and the flexing of the fabric under the feet will

tend to break the same loose and clear the foot-board. The projecting joints in the 40 fabric provide a roughened tread which increases the grip on the shoes and lessens the tendency to slip. The woven character of the fabric distributes the concentratedly applied load over a relatively large area and 45 lends strength to the structure.

Having described my invention what I claim as new and desire to secure by Letters Patent, is:—

1. A foot-board comprising a plurality of 50 sections each section having a framework, and an open mesh metal fabric tread secured thereto; and a support for jointly supporting adjacent ends of adjoining sections.

2. A foot-board having framework sections, each composed of longitudinal side rails, and transverse saddles, the saddles having legs to engage a roof; an open mesh metal fabric stretched across each section and secured thereto to form a tread; and a stirrup 55 for attachment to a roof and to which the adjacent saddles of adjoining sections may be anchored.

3. A foot-board having a pair of sections, 60 each comprising a pair of side rails, a pair of transverse saddles each having two end and one intermediate legs, and a wire open mesh metal fabric bridging the rails and saddles to form a tread; a stirrup for attachment to a roof and the intermediate legs of adjacent 65 saddles of adjoining sections; and a clip to protect the attachment of a stirrup with the roof.

In testimony whereof I hereunto subscribed my name.

JOHN C. LITTLE.
